UNITED STATES PATENT OFFICE.

EVERETT B. CUSHMAN, OF LINCOLN, NEBRASKA.

WATER-COOLER FOR ENGINES.

1,289,404.

Specification of Letters Patent. Patented Dec. 31, 1918.

Application filed March 16, 1918. Serial No. 222,816.

To all whom it may concern:

Be it known that I, EVERETT B. CUSHMAN, a citizen of the United States, and resident of Lincoln, in the county of Lancaster and

5 State of Nebraska, have invented new and useful Improvements in Water-Coolers for Engines, of which the following is a specification.

The present invention relates to cooling 10 appliances, and relates more particularly to devices for the circulation and cooling of the water or other liquid of an engine cooling system.

It is the object of the invention to provide 15 a water cooler for internal combustion engines of compact, simple and inexpensive construction for efficiently cooling the water by siphonic action without the use of a circulating pump, piping and like equipment.

20 Another object is the provision of a water cooler assembled with the engine water jacket in a novel yet simple manner, to avoid piping and similar connections, and to establish quite a rapid circulation of the water, 25 even without the use of a pump, the water jacket being so arranged as to interchangeably use a radiator, hopper cooler and pipe connections.

A further object is to provide a radiator 30 of novel and improved construction to efficiently carry out the principles of the invention.

With the foregoing and other objects in view, which will be apparent as the nature 35 of the invention is better understood, the invention resides in the construction and arrangements of parts hereinafter described and claimed, it being understood that changes can be made within the scope of 40 what is hereinafter claimed, without departing from the spirit of the invention.

The invention is illustrated in the accompanying drawings, wherein—

Figure 1 is a side elevation of an engine 45 and a radiator, embodying the features of the invention, assembled therewith.

Fig. 2 is a side elevation of a hopper cooler attached to the water jacket of the engine in place of the radiator.

50 Fig. 3 is a fragmentary side elevation of the water jacket showing how pipe connections can be used interchangeably with the radiator and hopper cooler.

Fig. 4 is a face view of the radiator, portions being broken away.

55

Fig. 5 is a side elevation thereof.

Fig. 6 is a fragmentary rear view.

In carrying out the invention, it is preferable to have the engine cylinder inclined, as seen in Fig. 1, so that its water jacket 1 is 60 similarly arranged, and said jacket is equipped at its upper side with the water outlet and inlet abutments 2 and 3, respectively, adjacent to the upper and lower ends of the jacket. By thus tilting the engine cylinder and its jacket and providing said jacket with the water outlet and inlet abutments, the engine is particularly adapted 65 for the direct attachment of the cooler.

The radiator 4 is attached directly to the 70 jacket 1, above the same but in an upright position, and for this purpose, said radiator is provided at one lower corner with an inclined portion 5 provided adjacent to its upper and lower ends with water inlet and outlet abutments 6 and 7, respectively, to complement and seat on the abutments 2 and 3, respectively, in order that the openings of 75 said abutments will register for the flow of water or other liquid in a circuitous path 80 between the jacket and radiator. The inclined portion 5 of the radiator with its water inlet and outlet therefore provide for the direct and effective connection of the radiator or cooler with the water jacket, 85 with the radiator extending upwardly and to one side from the jacket. The direct connection of the radiator with the jacket eliminates piping and like connections, and also dispenses with the necessity for a pump to 90 force circulation, inasmuch as a quite rapid circulation will be established by thermal siphonic action, the hot water rising in the jacket to the highest point where the abutment 2 is located and therefore passing 95 through the outlet of the jacket and inlet of the radiator to be cooled, and the cooled liquid in the radiator will pass to the bottom and flow back into the jacket through the abutments 7 and 3. The cooler water in 100 the jacket will naturally settle to the lowermost portion thereof and as it absorbs heat from the cylinder will rise and again flow to the radiator, to keep up the circulation as long as the engine is in operation.

105

Fig. 2 illustrates a hopper cooler used in

lieu of the radiator, so that it will be understood that the two coolers can be used interchangeably. The hopper cooler embodies a tank or receptacle 4' having at one lower corner the inclined portion 5' similar to the inclined portion 5 of the radiator, to adapt the tank 4' to the inclined jacket 1, and said portion 5' has the water inlet and outlet abutments 6' and 7' at its upper and lower ends to be secured to the abutments 2 and 3, respectively, for the circulation of water. The tank 4' has a partition or baffle 8 projecting from the portion 5' immediately above the water outlet toward the opposite side, to prevent the direct flow of the water from the inlet along the portion 5', to the outlet, and constraining the water to flow in the directions of the arrows in Fig. 2.

Fig. 3 depicts how pipe connections 6" and 7" can be fastened on the abutments 2 and 3, respectively, when such connections are desired.

Now taking up the detail construction of the radiator, which has characteristic features for its intended purposes, the same includes a sheet metal or other suitable casing 9 having an inner wall 10 circumscribing an opening 11 which extends through the casing for the passage of air, while the outer wall 12 of the casing extends around and is spaced from the inner wall 10, thus providing a chamber extending completely around the opening 11. The walls 10 and 12 have the lower inclined portions 13 and 14, respectively, extending diagonally from the bottom to one side, and providing the inclined portion 5 of the radiator as above described. Vertical water tubes 15 are arranged within the opening 11 and their upper ends extend through the upper portion of the wall 10, while their lower ends extend through the inclined portion 13 and bottom portion of said wall, so as to permit the water to flow downwardly in small streams from the upper portion of the water chamber to the lower portion thereof. Webs 16 of any suitable sort are assembled with the tubes 15 within the opening 11 to dissipate the heat to the atmosphere, and thus cool the water in the tubes 15, so that it flows downwardly therein. The casing 9 can be filled in any suitable manner, such as by providing the same with an upper filling neck 17 having a removable cap 18 thereon.

The abutments 6 and 7 which are assembled with the inclined portion 14 of the outer wall 12, are preferably part of a metal casting which fits against and is secured to the portion 5 of the radiator, said casting having the web 14 connecting the abutments 6 and 7 and riveted or otherwise secured to the portion 14. This casting also has the flanges 23 at its upper and lower ends extending at an angle from the abutments 6 and 7 and overlapping and riveted or other-

wise secured to the bottom and respective side of the wall 12, thus firmly fastening the casing 9 and casting together, and said casting or attaching member is provided at the opposite sides of the radiator with outstanding apertured ears 24 projecting from the abutments for the reception of bolts or other securing means to fasten the abutments 6 and 7 on the respective abutments 2 and 3 of the water jacket 1. The abutments 6 and 7 have the respective openings 20 and 21 to register with the openings of the abutments 2 and 3, for the flow of water therethrough as aforesaid, the portion 14 also having openings 22 registering with the openings 20 and 21. The opening 20 provides the inlet of the radiator below the short side thereof, while the opening 21 provides the outlet arranged substantially midway between the opposite sides, and in order to compel the hot water to flow upwardly from the opening 20, instead of flowing downwardly in the inclined passage between the portions 13 and 14, a partition or baffle 25 is provided between the opening 20 and said passage. This partition 25 is disposed above the opening 20, and has its upper edge soldered or otherwise secured, as at 26, to the wall 10 at the upper end of the portion 13, whereas the lower edge of the partition is soldered or otherwise secured, as at 27, on the portion 14 next below the opening 20. The water must therefore flow upwardly from the opening or inlet 20 in the vertical passage in the short side of the casing 9 to the upper portion of the water chamber for the downward flow of the water in the tubes 15 and vertical passage in the long side of the casing. From the lower ends of the tubes 15 the water flows along converging lines in the V-shaped passage in the lower portion of the casing below the tubes, to the opening or outlet 21 near the angle of said passage.

Fitted within that lower corner of the casing 9 opposite the portion 5, is a sheet metal angular or L-shaped reinforcing member 28, which fits against the wall 12 within the corner thereof. Said member is riveted or otherwise secured to the wall 12, and the upper end of the member has an inwardly extending stiffening flange 29. A flanged socket member 30 is secured to the inner side of the upright portion of the member 28, and has a threaded socket 31 opening through the member 28 and wall 12 for the reception of a bolt 32, as seen in Fig. 1, or other securing means for the attachment of a brace or support 33, to assist in bracing and supporting the radiator. The brace 33, as shown, is fastened on the crank casing 34 of the engine. A second socket member 30 can be provided near the top of the radiator, as shown in dotted lines in Fig. 4, for the attachment of a brace at this point, if desired.

An annular casing 35 for the fan used in forcing circulation of air is disposed in rear of the casing 9 around the opening 11, and is provided at its forward edge with outward turned flanges 36 soldered or otherwise secured to the back of the casing.

Having thus described the invention, what is claimed is:

1. The combination with a liquid jacket having an inclined side provided with an outlet and inlet near its upper and lower ends, of an upright cooler secured on said side of the jacket and having an inlet and outlet registering with the jacket outlet and inlet, respectively.

2. The combination with a liquid jacket having an inclined side provided with an outlet and inlet near its upper and lower ends, of an upright cooler having a lower inclined portion secured on said side of the jacket and provided with an inlet and outlet near its upper and lower ends to register with the jacket outlet and inlet, respectively.

3. The combination with a liquid jacket having an inclined side provided with outlet and inlet abutments near its upper and lower ends, of an upright cooler having inlet and outlet abutments seated on and secured to the aforesaid outlet and inlet abutments, respectively, for the siphonic circulation of the liquid.

4. The combination with a liquid jacket having an inclined side provided with outlet and inlet abutments near its upper and lower ends, of an upright cooler having a lower inclined portion provided with inlet and outlet abutments near its upper and lower ends seated and secured on the aforesaid outlet and inlet abutments, respectively.

5. An upright liquid cooler having a lower inclined portion to fit the inclined side of a water jacket and an inlet and outlet near the upper and lower ends thereof, respectively, for direct connection with the water jacket.

6. An upright liquid cooler having a lower inclined portion to fit the inclined side of a water jacket and an inlet and outlet near the upper and lower ends thereof, respectively, for direct connection with the water jacket and means between said inlet and outlet for preventing the direct flow of the liquid from the inlet to the outlet.

7. An upright liquid cooler having a lower inclined portion to fit the inclined side of a water jacket provided with inlet and outlet abutments near its upper and lower ends, respectively, for direct connection with the water jacket.

8. An upright liquid cooler embodying a casing having an opening for the passage of air and a circumscribing liquid chamber having a lower inclined portion below the opening to fit the inclined side of a water jacket and an inlet and outlet near the upper and

lower ends of said portion, respectively, for direct connection with the water jacket, the casing having vertical liquid circulating means in said opening communicating at its ends with said inlet and outlet.

9. An upright liquid cooler embodying a casing having an opening for the passage of air and a circumscribing liquid chamber having a lower inclined portion below the opening to fit the inclined side of a water jacket, and an inlet and outlet near the upper and lower ends of said portion, respectively, for direct connection with the water jacket, the casing having vertical liquid circulating means in said opening communicating at its ends with said inlet and outlet, and means within said portion for preventing the flow of liquid therein from the inlet to the outlet.

10. An upright liquid cooler embodying a casing having an opening for the passage of air and a circumscribing liquid chamber having a lower inclined portion at one corner below said opening provided with an inlet and outlet near its upper and lower ends, respectively, for direct connection to the inclined side of a water jacket, and vertical liquid tubes within said opening and communicating with the upper and lower portions of said chamber.

11. The liquid cooler specified in claim 14, and having a partition in said inclined portion near the inlet to prevent the flow of liquid from the inlet in said inclined portion to the outlet, whereby the inlet and outlet communicate with the upper and lower ends of said tubes, respectively.

12. An upright liquid cooler embodying a casing having a lower inclined portion provided with inlet and outlet openings near its upper and lower ends, respectively, and a supporting member secured to said inclined portion and having abutments with openings registering with the aforesaid openings.

13. An upright liquid cooler embodying a casing having a lower inclined portion at one side and an inlet and outlet near the upper and lower ends of said portion, respectively, a reinforcing member secured within the casing at the lower corner opposite the inclined portion, and a brace attaching member secured to the reinforcing member.

14. The combination with a liquid jacket having abutments at one side, one higher than the other, a water inlet in the lower abutment and a water outlet in the upper abutment, of a water circulating cooler at said side of the jacket having at one side, abutments fitting and secured detachably and rigidly to the aforesaid abutments and provided with openings for the flow of water, said cooler being arranged for the flow of water upwardly therein from the outlet of the jacket, and thence downwardly back into the jacket as the water cools.

15. The combination with a liquid jacket

4
having abutments at one side, one higher than the other, the lower one having a water inlet and the upper one having a water outlet, of a water cooler having an air opening, 5 water chambers above and below said opening, water circulating and cooling means connecting said chambers and located within said opening, and abutments at one side of said opening between said chambers fit-

ting and detachably secured to the aforesaid 10 abutments and having openings for the flow of water from the jacket outlet to the upper chamber and from the lower chamber to the jacket inlet.

In testimony whereof I hereunto set my 15 hand this 13th day of March, 1918.

EVERETT B. CUSHMAN.
